WHIPPING TOP

John T. Lancaster, 20231 Damman Ave.,
Harper Woods 36, Mich.
Filed Nov. 24, 1958, Ser. No. 775,940
1 Claim. (Cl. 46—67)

This invention relates to toys and refers more particularly to an improved whipping top toy, including a top having a concave upper surface and a low center of gravity, and a whip member having a two section lash with a frayed end.

In the past whipping tops have not been as commercially successful as the entertainment value of the top as conceived would indicate they should be. Certain structural and operating difficulties of the known types of whipping tops are believed to be responsible for public disinterest in this toy.

In the past the top members of whipping tops have had relatively high centers of gravity and smooth sides at least on the upper portion thereof. Such construction makes it difficult to start the top member spinning and to keep it spinning once it has been started. The top member is more unstable than necessary when it has a high center of gravity and the whip part of the toy tends to slip off the smooth sides thereof.

The whip members of whipping tops have in the past generally included lash members consisting of a single relatively flexible smooth, solid member or several such members attached to a short rod or handle. This whip construction adds to the slipping between the lash and the top member referred to above as no means is provided on either the lash or top to offer resistance to such slipping. Furthermore, in the prior art when the whip lash wore out the replacement thereof was generally complicated and required the purchasing of a special lash member.

It is therefore one of the objects of the present invention to provide a whipping top including a top member having a low center of gravity.

Another object is to provide a whipping top including a top member having annular grooves along substantially the full length thereof.

Another object is to provide a whipping top including a top member having a concave upper surface and a convex lower portion.

Another object is to provide a whipping top including a whip having a lash with a replaceable end section.

Another object is to provide a whipping top including a whip having a lash with a replaceable end section, the end of the replaceable end section being frayed.

Another object is to provide a whipping top including a whip having a lash comprising a fixed end section and a free end section, the free end section being relatively more flexible than the fixed end section.

Another object of the present invention is to provide a whipping top which is simple in construction, economical to produce, and efficient in operation.

Other objects and features of the present invention will become apparent as the description proceeds, especially when taken in conjunction with the accompanying drawings, illustrating a preferred embodiment of the invention, wherein:

FIGURE 1 is a side elevation of a top member of a whipping top according to the invention.

FIGURE 2 is a longitudinal section of the top member of FIGURE 1 taken on line 2—2 in FIGURE 1.

FIGURE 3 is a perspective view of a whip member of a whipping top according to the invention.

FIGURE 4 is a side elevation of another embodiment of a top member of a whipping top according to the invention.

2

In the embodiment of the invention illustrated in the drawings the reference numeral 10 generally indicates a top and reference numeral 12 generally indicates a whip. The top 10 and the whip 12 as shown make a complete whipping top according to the present invention. In use, the top 10 is started spinning by any means such as by hand. It is caused to continue spinning by whipping it with whip 12.

Top 10 may be made of wood in the form illustrated in FIGURES 1 and 2. The top shown is symmetrical about vertical axis 14 and is adapted to spin about this axis. Top 10 has a concave upper surface 16. The lower portion of top 10 has a pronouncedly convex surface 18 as shown. A metal long wearing tip 20 is provided on the lower end of top 10. The tip 20 is located on axis 14. The metal tip 20 is provided for spinning the top on concrete, tile, wood or materials of a like nature. Where it is found that surfaces may be damaged the tip 20 may be replaced with a tip made of wood, plastic, bone or other non-damaging material. A plurality of spaced apart annular grooves 22 as shown are provided on the exterior surface of top 10 over substantially the full length or height of the top. Top 10 may be made of any convenient material such as for example wood.

With the top 10 constructed as illustrated, having a concave upper surface 16 and a convex lower surface 18, the center of gravity of top 10 will be relatively low. The low center of gravity of applicant's top 10 produced by the particular configuration thereof as illustrated greatly reduces the tendency of the top 10 to fall from an upright position with axis 14 substantially vertical as it is when it is spinning to a position on its side with axis 14 substantially horizontal. The ease with which the top 10 is started spinning is therefore increased. Also, since the top tends to tip less easily it is less difficult to keep the top 10 spinning by whipping it with whip 12.

The grooves 22 on applicant's top 10 are provided to aid in starting the spinning motion of the top and also coact with lash 24 on whip 12 to keep the top spinning.

40 The top 10 may be started spinning by grasping it in the hand and rotating it while holding it vertical with wearing point 20 resting on a relatively smooth dense surface. Alternatively the top may be held loosely with axis 14 in a vertical position and struck with whip 12 to start it spinning. The annular grooves 22 serve to provide a surface which may be easily grasped. The grooves also serve to keep the whip lash 24 from slipping off the surface of the top 10 when the top is whipped.

Whip 12 of the whipping top toy includes a rigid rod

50 or handle 26 and a whip lash generally indicated 24. Rod 26 as shown is a short cylindrical section having an opening 28 therethrough at right angles to the axis thereof of near one end 30. Lash 24 includes a fixed end section 32 and a free end section 34. The fixed end section 32 of lash 24 is relatively longer than the free end section 34. Lash 24 is flexible. The free end section 34 of lash 24 is more flexible than the fixed end section 32.

55 Section 32 of lash 24 is secured to whip handle 26 by passing end 36 of lash section 32 through opening 28 in end 30 of handle 26, returning it along the surface of the handle, and fixing the end 36 to rod 26 by convenient means such as staples 38. End 40 of section 32 of lash 24 is returned along itself to form a loop 42 in the end thereof. End 40 is secured to the end portion of section 32 by convenient means such as tape 44.

60 Free end section 34 of lash 24 as shown is attached to loop 42 of fixed end section 32 by means of looping the mid-portion 46 of section 34 about one side of loop 42 of the fixed end section 32 and passing ends 48 and 50 through the loop 42 from the other side thereof. In this manner free end section 34 is securely fastened to

fixed end section 32 of lash 24 and lash 24 is provided with a pair of flexible ends 48 and 50 for striking top 10. The ends 48 and 50 are frayed as shown at 52 and 54.

Handle 26 may be wood, plastic, metal or other suitable rigid, light, relatively strong material. The fixed end section 32 of lash 24 may be of any material which would give a firm tough pliable but not limp effect when swinging. It should swing as a whole mass rather than a wriggly piece of matter. Leather, nylon cordage, woven glass and plastic tubing are suitable materials for end section 32. The material from which end section 34 of lash 24 is made must be more flexible than that of section 32, strong, and capable of being frayed at the ends as shown at 52 and 54. Common sash cord is such a material. Other similar woven or laced material may also be used for end section 34.

End section 32 of lash 24 must be less flexible than end section 34 so that as the top 10 is whipped with the whip 12 the section 32 is sufficiently rigid to provide end 34 with the proper snap to impart a sufficient force to top 10 to maintain it in a spinning attitude. The greater flexibility of end section 34 allows end section 34 to wrap around top 10 when top 10 is whipped with whip 12 thereby allowing greater whip contact with the top 10 and also allowing grooves 22 to coat with member 34 to keep it in contact with top 10 longer thereby helping to impart more spinning force to top 10.

The connection between fixed end section 32 and free end section 34 of lash 24 at loop 42 as shown is such as to allow removal and replacement of free end section 32. Thus, as free end section 32 is worn out in use by whipping top 10 therewith it may be replaced. Since the free end of lash 24 is the only element of the toy subject to substantial wear the toy is therefore substantially permanent. This is especially true since the free end 34 may be of sash cord which is cheap and easily obtainable.

The frayed ends 52 and 54 are provided on the ends 48 and 50 of free end section 34 of lash 24 to provide greater traction between the lash 24 and the surface of top 10 to impart a spinning motion to the top 10 when it is struck by whip 12. The frayed ends serve a double function in the cooperation between top 10 and whip 12. They are easily received within grooves 22 to prevent lash 24 from slipping off of top 10 without transferring maximum rotational force thereto. They also serve to remove the whip lash 24 from top 10 in a gradual manner by leaving the surface of the top 10 in a distributed whipping movement thereby causing minimum disturbance to the balanced condition of the top 10 at this time.

In FIGURE 4 a modified top 56 is illustrated. Top 56 like top 10 has a concave upper surface 58 and a low center of gravity. Annular grooves 60 are also provided on the exterior surface of top 56. In addition the surface of top 56 is convex between grooves 60 as shown at 62. Like top 10, top 56 is provided with a wearing point 64. As previously indicated in connection with top 10 the grooves 60 serve to keep the whip lash from

slipping off top 56 when the top is whipped in use and provide a surface which is easily gripped. The convex surfaces 62 serve the same function.

In use either top 10 or top 56 of the whipping top toy 5 may be given an initial spinning motion about a vertical axis such as 14 of top 10 by any convenient method such as by hand. The top is then whipped with whip 12 to cause it to continue to spin. For best results the whipping should be accomplished so that only the more flexible free end 34 of lash 24 of whip 12 makes contact with the spinning top. Proper whipping of the top with the whip will cause the top to continue to spin indefinitely.

What I claim as my invention is:

A whipping top toy comprising a top adapted to spin about a vertical axis therethrough, said top having a substantially entirely concave top surface and side and bottom surfaces substantially entirely convex whereby said top has a center of gravity substantially below the mid-height thereof, axially spaced apart annular grooves on 15 said top over substantially the entire side and bottom exterior surfaces thereof, and a whip for imparting a force to said top while it is spinning to cause said top to continue to spin including a rigid handle and a lash secured to one end of said handle, said lash having a fixed 20 end section one end of which is secured to the handle at one end of the handle and a free end section the center of which is removably secured to the other end of the fixed end section, the fixed end section of the lash being 25 more flexible than the rigid handle and less flexible than the free end section whereby on swinging the whip in an arc the fixed end section of the lash offers substantial air resistance and closely follows the movement of the handle while the free end section offers little air resistance and does not follow the movement of the handle closely 30 but wraps readily around the top on contact therewith to provide a substantial area of contact between the top and the free end section of the lash over which force may be transferred from the whip to the top, said free end section of the lash having a pair of frayed free ends 35 to provide a wiping action on the side surfaces of the top during force transfer from the whip to the top to increase the efficiency of the force transferred therewith.
